UNITED STATES PATENT OFFICE

HANS C. GRONBECK, OF CHICAGO, ILLINOIS

INTERNAL COMBUSTION ENGINE

Application filed September 18, 1930. Serial No. 482,882.

My invention relates to improvements in internal combustion engines, and it consists in the combinations, constructions, and arrangements herein described and claimed.

5 An object of my invention is to provide an internal combustion engine in which novel means is provided as a substitute for the usual crankshaft construction, whereby a maximum power efficiency is attained through 10 the medium of a relatively simple construction.

A further object is to provide a device of the type described which is constructed in such a manner that gears and the like are 15 entirely dispensed with in connection with the valve operating mechanism, etc.

Other objects and advantages will appear in the following specification, and the novel 20 features of the invention will be particularly pointed out in the appended claims.

My invention is illustrated in the accompanying drawing, forming part of this application, in which

25 Figure 1 is a side elevation of an engine embodying my invention,

Figure 2 is an end elevation, and

Figure 3 is a sectional view of the piston connection.

In carrying out my invention, I make use 30 of a base 1 provided with a post 2 and bearing elements 3. In the drawing, I have shown the base as being mounted upon a concrete foundation 4 having a pit 5 for accommodating a flywheel 6. The latter is mounted upon a shaft 7 which is supported by the bearings 3.

A cylinder 8 is associated with the post 2 and is provided with a piston 9 having a rod 10 connected thereto. The piston is also provided with a push rod 11 having its outer end formed to simulate a pawl, which at certain times is disposed within a recess 12 in the periphery of the flywheel, as shown in Figure 1. The push rod is normally held in engagement with the flywheel through the medium of a spring 11' which may be connected with the piston. A lever 13 is operatively connected with the rod 10 and is pivotally mounted at 14 upon one of a pair of brace members 15. One side of the flywheel 6 is provided with an elliptical groove 16 within

which a roller 17 associated with the arm 13 rides.

The shaft 7 is provided with a cam 18. The cam has contact with a roller 19 associated with a bell crank lever 20 which is pivotally mounted at 21 upon a lug 22 associated with the post 2. The bell crank lever bears against a valve stem 23. The latter is normally held in its closed position through the medium of a spring 24. The bell crank lever is shown in connection with the exhaust valve in the present instance. The intake valve ordinarily may be operated independently of a mechanical device, but it will be understood, however, that the intake valve may be similarly operated. The intake valve is indicated upon the opposite side of the flywheel in Figure 2.

In operation, the flywheel rotates in a counterclockwise direction, as when viewing Figure 1. The piston 9 is shown at the completion of its outward movement. The push rod 11 of course rotates the flywheel 6. The engine in the present instance embodies a structure wherein four strokes are attained during each revolution of the flywheel and one power stroke during each revolution. During the operation of the device, the outer end of the push rod 11 is moved into the recess 12 and in proper timed relation with the explosion. As the piston is moving outwardly, the push rod will of course rotate the flywheel 6. The groove 16 causes the arm 13 to move the piston 9 in a reciprocatory manner. In Figure 1, I have shown the groove 16 as having an irregularly formed portion. This portion is positioned so that the roller 17 moves therethrough during the power stroke. This specific slot construction permits a quicker action of the piston during its power stroke. This feature increases the efficiency of the mechanism. In viewing Figure 1, it will be noted that the groove 16 is constructed so that one explosion is provided for each revolution of the flywheel. An important feature in connection with my invention is the fact that the push rod 11 is positioned relatively far from the axis of the flywheel so that the push rod delivers a maximum power stroke. In addition to this, I have eliminated the usual crankshaft con-

55 60 65 70 75 80 85 90 95 100

struction and provided a device in which the groove 16 may be formed for providing a variable number of power strokes during each of its revolutions.

Incidentals, such as spark plugs, carburetors, and the like, are not shown in the present instance. These devices are of course well known in the art and therefore require no detailed description. The ignition system 16 will of course be operated from the shaft 7 through the medium of any suitable mechanism.

I claim:

1. A reciprocating engine piston comprising a flywheel having an irregular groove in its face and an abutting element in its periphery, a cylinder provided with a piston, a pivotally supported lever hingedly connected with the piston and having a portion disposed within said groove, and a push rod movably connected with the piston and arranged for engaging said abutting element during the power stroke of the engine.
2. A reciprocating engine piston comprising a flywheel having an irregular groove in its face and an abutting element in its periphery, a cylinder provided with a piston, a pivotally supported lever hingedly connected with the piston and having a portion disposed within said groove, a push rod movably connected with the piston and arranged for engaging said abutting element during the power stroke of the engine.
3. A reciprocating engine piston comprising a flywheel having a continuous irregular groove in its face and an abutting element in its periphery, a cylinder having a reciprocating piston, a bearing for the flywheel, a base rigidly supporting the bearing and the cylinder, a brace rod rigidly connected to the cylinder and the bearing, a lever being pivotally secured by the brace rod and hingedly connected to the piston and having a roller operatively disposed in the continuous groove, and a pawl pivotally connected to the piston for engaging said abutting element during the power stroke of the engine, said lever and said grooved flywheel coacting to continue the reciprocating movement of the piston after each power stroke.

HANS C. GRONBECK.
